UNITED STATES PATENT OFFICE.

MORRIS N. CASTLEMAN, OF ROCKFORD, ILLINOIS, ASSIGNOR TO GEORGE E. KING AND HENRY H. PALMER, OF SAME PLACE.

CHURN.

SPECIFICATION forming part of Letters Patent No. 417,310, dated December 17, 1889.

Application filed February 13, 1888. Serial No. 263,927. (No model.)

To all whom it may concern:

Be it known that I, MORRIS N. CASTLEMAN, a citizen of the United States, residing at Rockford, in the county of Winnebago and 5 State of Illinois, have invented certain new and useful Improvements in Revolving-Barrel Churns, of which the following is a specification.

This invention relates partly to the form 10 and construction of the open end of a churn and partly to the manner in which the cover is secured thereto.

The object of this invention is to produce a 15 revolving churn the aperture whereof is so formed and constructed that therethrough ready and complete access may be had to all parts of the interior thereof.

A further object of this invention is to provide an improved means of securing covers to 20 revolving churning.

Referring to the accompanying drawings, which form a part of this specification, Figure 25 1 is an isometric view of the upper portion of a churn provided with my improvements. Fig. 2 is a view of a vertical section of the upper portion of the churn through the dotted line x x of Fig. 1. Figs. 3, 4, and 5 are isometric views, in detail, of parts of the churn 30 illustrated in Fig. 1, and will be fully described hereinafter. Fig. 6 is a view of a detached portion of Fig. 2.

Like letters of reference indicate corresponding parts throughout the several views.

A represents a revolving-barrel churn having 35 a croze A' in the end thereof.

A² represents an annular recess formed by removing the entire inner portion A³ of the chine A⁴ of the churn A.

B represents a chine-ring of proper form 40 and dimensions to be seated in the annular recess A² and to be included therein, so as not to project inward beyond the inner surface of the churn in the chine A⁴, and having a horizontal annular flange B' adapted to enter the croze A' therein, and a vertical annular flange B² projecting above the chine thereof.

C represents a removable churn-cover, circular in form and provided with a semi-rectangular peripheral groove C', which contains 50 cork C² or other suitable elastic packing de-

signed to engage and form a tight joint with the annular flange B² of the chine-ring B.

D represents a metallic casing that completely incloses the periphery and upper peripheral angle of the cover C.

D' represents retaining-lugs projecting from the casing D.

E represents an arm provided with an in-curving hook E', adapted to engage with the lugs D' of the casing D, and having a vertical slot E² extending through the lower portion thereof, and a short horizontal stud E³ projecting outward therefrom.

F represents a boss having a vertical slot F' in the outer face thereof and provided with a horizontal pintle F², which projects outward 65 from the center of the slot F'.

F³ represents holes in the boss F, through which bolts are passed to secure the same to the churn A.

F⁴ represents a pin-hole in the pintle F².

G¹ represents a cam having a circular opening G' therein and provided with a handle G² and a slot or groove G.

G³ represents a pin-hole for retaining the 75 cam G upon the pintle F².

After the bosses F have been bolted to the churn, the slots F' therein being vertical, the pintles F² are inserted through the slots E² in the arms E and the openings G' in the 80 cams G¹, and the studs E³ are made to engage with the slots G of the cam. Next revolve the cover C until the lugs D' pass under the hooks E'. Depressing the handles G² of the cams G¹ forces the arms E downward, and the hooks 85 E' are thereby caused to descend and secure the cover to the churn. A reverse motion of the handles G² releases the cover C.

The "ring-head" heretofore used to connect covers with revolving churning is inconvenient 90 and unsatisfactory in several important respects. In the first place the ring-head prevents commodious access to the interior of a churn by diminishing the diameter of the aperture leading thereto one-fourth to one-third; second, it presents a serious obstacle to the removal from the churn of its contents; third, its use renders it difficult to properly cleanse the inside of the ring-head and that portion of the interior of the churn adjacent 95 100

thereto, and, fourth, its employment makes it necessary to attach a heavy compensating weight to the bottom of the churn to balance the same.

5 All the disadvantages above enumerated are completely avoided by using a chine-ring like the one herein shown and described in lieu of the ring-head heretofore generally used in the construction of revolving churns.

10 By employing the cams and attachments shown greater and more evenly-distributed retaining force can be applied to churn-covers than in any other practical manner.

I claim—

15 1. The combination, with a revolving-barrel churn having an annular recess therein along the entire inner portion of a chine thereof, of a chine-ring seated and included in the annular recess and provided with a vertical annular flange projecting above the chine of the churn, substantially as described, and for the purpose specified.

20 2. In combination, an arm provided with an incurving hook having a vertical slot extending through the lower portion thereof and a horizontal stud projecting outward therefrom, a boss having a vertical slot in the outer face thereof and provided with a horizontal pintle projecting outward from the center thereof, and a cam mounted on said pintle and engaging with and operating the said arm through

the medium of the aforesaid horizontal stud, substantially as set forth.

3. The combination of a churn, a removable head, and a chine-ring fixed in the churn, said chine-ring fitted with a projection to enter the croze and extending upward along the interior of the churn and extending above the chine of the churn to receive the removable head, substantially as set forth.

4. The combination of a churn, a removable head, and a chine-ring, said chine-ring fitted with a projection to enter the croze and extending upward along the interior of the churn and extending above the chine of the churn to receive the removable head, and means for securing the removable head to the chine-ring, substantially as set forth.

5. The combination of a churn, a removable head, and a chine-ring, said churn having an annular recess therein along the entire inner portion of the chine thereof, said chine-ring seated and included in the annular recess and provided with a vertical flange projecting above the chine of the churn to receive the removable head, and means for securing the removable head to the chine-ring, substantially as set forth.

MORRIS N. CASTLEMAN.
